UNITED STATES PATENT OFFICE.

FRANK A. GILCREST, OF PASADENA, CALIFORNIA.

HEAT-NON-CONDUCTING FABRIC.

1,371,754.

Specification of Letters Patent. Patented Mar. 15, 1921.

Application filed July 25, 1919. Serial No. 313,242.

To all whom it may concern:

Be it known that I, FRANK A. GILCREST, a citizen of the United States, residing at Pasadena, in the county of Los Angeles and 5 State of California, have invented certain new and useful Improvements in Heat-Non-Conducting Fabrics; and I do hereby declare the following to be a full, clear, and exact description of the invention, such as 10 will enable others skilled in the art to which it appertains to make and use the same.

This invention relates to a new heat non-conducting material adapted for use in the construction of body garments, blankets, 15 over-coats, and the like.

The object is to provide a freely flexible material or fabric, preferably embodying outer layers of paper and an interposed layer of diatomaceous earth, which latter 20 possesses to a high degree heat non-conducting qualities.

The invention also provides a fabric or material of this character which may be easily manufactured, and in which the earth 25 or non-conductor used is held from shifting out of place between the layers.

With these and further objects in view, as will in part hereinafter become apparent and in part be stated, the invention comprises certain novel constructions, combinations and arrangements of parts as subsequently specified and claimed.

In the accompanying drawings,—

Figure 1 is a fragmentary plan view of a 35 portion of material or fabric constructed according to this invention.

Fig. 2 is a section taken through the same substantially on the plane indicated by line 2—2 of Fig. 1, the section being enlarged 40 and showing the cells or pockets formed between the outer layers of the material.

It is found that diatomaceous earth possesses heat non-conducting and vibration non-conducting qualities to a high degree, 45 and to admit of the use of this earth in the formation of body and like coverings, the present invention provides a novel construction of casing or inclosure combined with the earth for holding the latter from 50 shifting and to thus insure the uniform

thickness of the completed fabric throughout its extent.

Referring to the drawing by numerals, 10 and 11 designate the outer layers of paper which form the casing in which the body of infusorial earth 12 is placed. The infusorial earth is preferably diatomite on account of its high degree of non-conductivity of heat, shock, moisture, and the like. To close the 55 marginal edges of the fabric, one of the layers, such as the layer 11, may have an extended marginal edge portion 13 overlapped upon the marginal edge portion of the other layer 10 to form a casing there- 60 with, the overlapping portion 13 being secured to the layer 10 by a line of stitching 14. The insulation or packing 12, which is in a finely comminuted state, is held from shifting between the layers 10 and 11 by the formation of a large number of relatively 65 small pockets or bags formed by lines of stitching 15 which extend preferably diagonally with respect to the length of the outer layers 10 and 11, and which are crossed. This arrangement of the lines of 70 stitching 16 forms a large number of pockets of substantially diamond formation and within which the earth 12 is retained. The lines of stitching 15 are formed to draw the 75 portions of the layers 10 and 11 between the diagonal rows of pockets substantially together, as shown in Fig. 2, and thus sub- 80 stantially close the marginal edges of the pockets and prevent the escape of the earth 12 from the pockets. The fabric or ma- 85 terial is thus quilted, and as the diatomaceous earth is in the form of a fine powder, it provides a filling which is relatively soft and pliable, admitting of the free use of 90 the fabric produced.

The material thus produced is relatively light in weight as compared with its non-conducting qualities, and is adapted particularly for use in camps, and other exposed places, where it is necessary to keep the body warm and where weight and space 95 must necessarily be reduced.

The layers 10 and 11 of paper are of flexible, soft texture, and are at the same time tough and durable. The paper is water- 100

proofed by known processes so as to give it capacity to resist bad weather and trench environments and to insure comfort of the wearer notwithstanding inclement conditions.

What I claim is:—

A body covering fabric comprising a flexible casing, a body of diatomaceous earth filling the casing, and crossing lines of 10 stitching secured to the opposite sides of

the casing for drawing the same together to hold the earth from shifting in any direction in the casing.

In testimony whereof I affix my signature in presence of two witnesses.

FRANK A. GILCREST.
